UNITED STATES PATENT OFFICE

JOHN C. OLSEN, OF CHICAGO, ILLINOIS, ASSIGNOR TO FLEXIBLE STEEL LACING COMPANY, OF CHICAGO, ILLINOIS, A CORPORATION OF ILLINOIS

PUNCH

Application filed April 17, 1931. Serial No. 530,753.

This invention relates to improvements in punches and more particularly punches adapted for making holes in belts of leather, canvas and the like to permit application of belt fasteners thereto.

One object of the invention is to provide an efficient, rugged and durable punch of economical construction for punching holes in articles such as belts and the like.

Specific objects of the invention are to provide a hollow punch of the character above indicated and having a wavy or fluted edge easy to force through the material operated upon and wherein the cutting edge is easily maintained in sharp condition, the construction being further characterized by the fact that any tendency of the punch to shift out of line as it is forced through the material is minimized or entirely eliminated.

Other objects of the invention will more clearly appear from the description and claims hereinafter following.

In the drawing forming a part of this specification, Figure 1 is a perspective view of a hand punch embodying my improvements, said figure being substantially full size. Figures 2 and 3 are transverse, sectional views corresponding to the lines 2-2 and 3-3, respectively, of Figure 1 upon enlarged scales. And Figures 4 and 5 are longitudinal, diametrical, sectional views corresponding substantially to the lines 4-4 and 5-5, respectively, of Figure 2.

The improved punch, as shown, comprises a solid top or head end 10, an intermediate open sided section 11 and a hollow tubular terminus or active punching end 12. All portions are of circular cross section, the head or striking end being preferably beveled, as indicated at 13 and, for convenience in extracting the punch, the head end may be provided with a diametrical opening 14 to receive a pin or the like so as to obtain a better purchase in pulling the punch out of the belt or other article operated upon.

The intermediate section 11 is provided with an elongated opening 15 along one side thereof, which serves as an ejector opening for the punchings that are pushed up through the active end of the punch, as will be understood.

The lower tubular terminal section 12 is of reduced external diameter, as compared with the intermediate and head sections, the intermediate and terminal section 12 being united by a tapered portion 16, as shown. The terminal section 12 has an interior opening 17 communicating with the discharge or ejector opening 15, said terminal portion being of uniform inside and outside diameter throughout its entire length and preferably, on account of the materials on which it is intended to be used, the thickness or cross section of the wall of the terminal section 12 will be maintained not less than .015 inches and not greater than 0.50 inches by reason of which the punch will not collapse, yet at the same time will permit of easy passage of the punch through the material. I have found that a satisfactory thickness is approximately .03 inches.

The lower cutting edge of the section 12 is of special formation having, as shown, two diametrically disposed portions 18-18, which are longitudinally in advance of the intervening edge portions 19-19, the edge consisting of what may be termed approximately ogee curves, as viewed in side elevation. The cutting edge is also beveled downwardly and inwardly toward the axis of the punch, as indicated at 20, around the entire circumference, said bevel being maintained within the limits of 25° and 65° angles with reference to the axis. I have found that a bevel of approximately 45° is satisfactory and may be easily maintained. As will be evident from the drawing, the curves of the ogee formation are relatively shallow or of short amplitude, so that no sharp or narrow pointed projections are formed.

By making the terminal punching portion 12 of uniform cross section and diameter, and of a length substantially in excess of the thickness of the material to be punched, and 5 by having circumferentially spaced portions as 18—18 of the cutting edge in advance of the intervening portions, I have found that the punch will pass readily through any ordinary thickness of belting without danger of 10 crushing or distorting the punch and with a clean cut hole. By having portions of the cutting edge as 18—18 in advance of the intervening portions, the portions 18 obviously initially engage the material, start the cut 15 at two circumferentially spaced points, the remainder of the cut for the punching being obtained by a progressive circular shearing effect. Furthermore, by making the number of advanced cutting portions 18 an even number, the cutting action is balanced so as to prevent tendency of the punch to be shifted laterally in its passage through the material.

With a punch constructed as hereinabove described, the cutting edge may be easily 25 maintained sharp by suitable grinding at intervals; the punch may be manufactured at relatively small cost and is of rugged construction, assuring long life.

Although I have herein shown and described what I now consider the preferred manner of carrying out my invention, the same is merely illustrative and I contemplate all changes and modifications that come within the scope of the claims appended hereto.

35 I claim:

1. A punch having a solid head, an intermediate hollow section with a lateral discharge opening for the punchings, and a hollow tubular terminal section of uniform cross 40 section throughout and of lesser external diameter than that of the intermediate section, said terminal section having an active cutting edge beveled in longitudinal section, said edge being formed with a plurality of uniformly, circumferentially spaced portions thereof disposed longitudinally in advance 45 of the intervening portions, said cutting edge, in elevation, presenting a plurality of substantially ogee curves.

50 2. A punch for leather, canvas and similar materials comprising: a head and intermediate hollow section; and a terminal hollow tubular section, said terminal section being of uniform size and cross section throughout 55 and provided with an active cutting edge beveled in longitudinal section, said edge being so formed as to present a plurality of substantially uniformly circumferentially disposed ogee curves, as viewed in side elevation.

60 3. A punch in accordance with claim 2 wherein said ogee curves are relatively shallow and the thickness of said tubular terminal section is between the minimum and maximum limits of .015 and .050 inches.

65 4. A punch in accordance with claim 2

wherein said intermediate hollow section is of larger outside diameter than the said terminal section and also of thicker cross section, said intermediate section being provided also with a discharge opening for the punchings.

In witness that I claim the foregoing I have hereunto subscribed my name this 8th day of April, 1931.

JOHN C. OLSEN.
